UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

AUTOMATIC TELEPHONE SYSTEM.

1,247,770.

Specification of Letters Patent. Patented Nov. 27, 1917.

Application filed January 31, 1916. Serial No. 75,328.

To all whom it may concern:

Be it known that I, SAMUEL B. WILLIAMS, Jr., a citizen of the United States, residing at Brooklyn, in the county of Kings and 5 State of New York, have invented certain new and useful Improvements in Automatic Telephone Systems, of which the following is a full, clear, concise, and exact description.

10 This invention relates to automatic telephone systems and particularly to systems of the type in which switching apparatus at the central office acts automatically to find and make connection with a calling subscriber's line.

15 In systems of the type toward which the present invention is particularly directed, a number of line finding and connecting circuits are provided for the common use of 20 a larger number of telephone lines; and when any one of the telephone lines initiates a call, one or another of the line finding switches in which the finder circuits terminate is automatically made operative to connect 25 with the calling line, the finder switch that is made operative being one that is at the time disengaged or idle. The principal object of this invention is to provide an improved control system for use in such an organization 30 to insure one finder circuit, and one only, being made operative to connect with a calling line when a call is initiated; to prevent the finder circuit that is thus made operative from establishing connection 35 with more than one line; and to simplify and improve the part of the organization which has to do with the preparing or assigning of the finder circuits and switches for serving the calling line.

40 The novel features of the invention through the provision of which the above mentioned and other advantageous results are attained, will be explained by reference to the accompanying drawings, in which a 45 preferred embodiment of the invention is shown, and in which Figures 1, 2 and 3 taken together, and with Fig. 1 at the left and Fig. 3 at the right of Fig. 2, illustrate the circuit organization employed in this particular embodiment.

50 In the organization illustrated, four metallic circuit telephone lines are shown extending from subscribers' stations A', A², B', and B² to the central office where they 55 terminate upon stationary contact terminals

of two line finder switches C' and D'. Each line has connection at the central office through the resting contacts of a cut-off relay 11 with the windings of a line relay 12 between which is bridged a battery 13. 60

The lines are divided into groups at the central office, the lines from stations A' and A² being two of a number of lines that are assumed to constitute group A, and the lines from stations B' and B² being assumed to 65 be two of a number of lines that are assumed to constitute group G. Groups A and B may be two of a number of groups of lines that are served by the finder switches C' and D', such other groups being arranged 70 similarly to the two groups that are shown.

Each group of lines has associated with it certain group apparatus, consisting in the present instance of relays 19 and 24 and a sequence switch 100. This group apparatus 75 is under the control of the line relays of the corresponding group of subscribers' lines, and through the medium of the starting circuit apparatus E, common to all of the groups, controls the starting of one of the 80 line finders to find a calling line, and also through the medium of the trip magnets 16 and 17, common to all of the line finder switches, controls a preliminary group selection by whichever line finder that is 85 started.

The finder switches C' and D' are two of a larger number which may be provided for serving all of the lines of the various groups, such additional finder switches being similar 90 to those which are shown. Each of the finder switches serves as the connecting member at one end of an associated finder circuit, C, D, the other end of which may be provided with a cord selector through 95 the medium of which an idle connecting cord circuit may be selected to extend the circuit of a calling line to that of a called line. The cord selectors and connecting cord circuits, which may be assumed to be of any 100 suitable and well-known type, are not shown as they form no part of the present invention.

As the finder switches in themselves are not novel, they are shown merely diagrammatically. These switches may be substantially like the switch illustrated and described in patent to James L. McQuarrie No. 1,177,044, issued March 28, 1916. 105

The organization involves the use of se- 110

quence switches, which are shown diagrammatically and may be of the type disclosed in Patent 1,127,808, issued February 9, 1915, to Reynolds and Baldwin. The electromagnetically controlled motor or driving mechanism of these switches is indicated diagrammatically in the parts designated 100 and 200 in the drawings, and the associated switch contacts are designated 101 to 103 inclusive, in the case of sequence switches 100, and 201 to 218 inclusive, in the case of sequence switches 200. The numerals applied to the sequence switch contacts 101 and 201, indicate the only positions of each switch in which the associated contacts are open; the numerals applied to the other contacts of each switch, indicate the position of each switch in which the associated contacts are closed.

20 The commutators of the line finder switches are shown at the tops of their respective switches in Fig. 2 of the drawing. Instead of showing the circuit connections with such of these commutator segments as are involved in the present disclosure, such circuit connections are merely indicated by correspondingly lettered squares on Fig. 3 of the drawing.

The organization disclosed will be best presented, it is believed, by proceeding directly to a description of the operation of the system.

When one of the subscribers, say the subscriber at station A', takes his telephone from his hook, his line relay 12 is energized and closes its contact. This establishes a path to ground from conductor 18, which is multiply connected to the armatures of all of the line relays in the group which it serves.

40 If it be assumed that the sequence switch 100 of the group A in which the line from station A' terminates, is in its normal or first position, the grounding of the conductor 18 completes an energizing circuit 45 for the group relay 19 by way of sequence switch contacts 103 closed in positions 18 $\frac{3}{4}$ to 1 $\frac{1}{4}$ of the switch. Relay 19 thereupon closes its contact 21 and assuming that the starting circuit relays 22 and 23 are inert, 50 completes a circuit for the energization of the group relay 24, this circuit including the right-hand winding of relay 24, contact 21 of relay 19, resting contact 25 of relay 22 and resting contact 26 of relay 23. Relay 55 24 thereupon operates and closes its contacts 27 and 28. The closure of the contacts 27 completes a circuit that includes the left-hand winding of the relay 24 and the winding of the line finder trip magnet 16 in parallel branches, and the winding of the starting relay 22 in the common portion of the circuit. The energization of the trip magnet 16 sets the tripping mechanism of all 60 of the line finders to trip the corresponding 65 set of brushes of whichever line finder is

started, and thus to effect the preliminary selection of the group of lines in which the calling line is located. The energization of the left-hand winding of group relay 24 serves to lock up this relay independently of the circuit of the right-hand winding; and the energization of starting relay 22, by breaking the resting contact 25, interrupts the path over which the initial energization of group relay 24 by way of its right-hand winding was first effected, and starts a finder switch in a manner hereinafter to be described.

The closure of contacts 28 of group relay 24 effected in the initial energization of the relay, completes the circuits of the motor magnet of sequence switch 100 by way of sequence switch contact 102 closed in the first position of the switch. This causes the sequence switch to move out of position 1; 85 and as the controlling contacts 101 of the switch are closed in all except the first position, the sequence switch makes a complete rotation, at the end of which it again comes to rest in its first position. In moving out of its normal position, the sequence switch opens the circuit of conductor 18 in sequence switch contacts 103, and does not close it again until the switch reaches its 18 $\frac{3}{4}$ position that is, until it is just at the point of coming to rest in its normal position.

The starting of a line finder to find and complete connection with the calling line is effected through the medium of a conductor 29 which is under the control of the relay 22 of the group of starting apparatus E, common to the groups A and B. When relay 22 is energized as a result of the energization of relay 24, it closes in its front contact 25 a path to ground for the starting conductor 29 by way of the resting contact 26 of relay 23. The grounding of the conductor 29 energizes the motor magnet of the sequence switch 200 of one of the finder circuits that has been preselected and is standing in readiness to take a call.

As many finder circuits may be provided as are necessary to handle the calls from the associated groups of subscribers' lines. In the present instance two finder circuits, the first and last of the series, are shown complete with respect to the elements involved in the operation here to be described, while such parts of a circuit intermediate in the series are illustrated as serve to show the relation of this circuit with its associated circuits.

The manner of effecting the preselection of the finder circuit to place it in readiness to respond to a calling line will be described hereinafter. For the present it will be sufficient to assume that the finder circuit C which terminates in the finder switch C' is the circuit that has been preselected and is standing in readiness to take the next call.

The preselected condition is one in which the sequence switch 200 of the finder circuit is standing in its second position. This being the case, the grounding of the starting 5 conductor 29 by the operation of the relay 22, completes a path for the energization of relay 30 of finder circuit C by way of the left-hand winding of that relay, sequence switch contacts 206 closed in the second position, starting conductor 29, front contacts 25 of relay 22, and resting contacts 26 of relay 23. Relay 30 in operating closes in its front contact 31 an energizing circuit for the motor magnet of sequence switch 200 by 10 way of sequence switch contacts 202 and 208 closed in position 2. The sequence switch thereupon moves out of position 2, and when it reaches position 3 completes a circuit for the flow of current through the up-drive 15 magnet 32 of the line finder by way of conductor 20, contacts 207 of the sequence switch, closed in position 3, front contacts 31 of the relay 30, and contacts 208 closed in positions 18 to 14 and 2 to 7 of sequence 20 switch 200 to ground. The consequent energization of up-drive magnet 32 of finder switch C' causes it to force the elevating bar of the brush carrying rod into engagement with the associated driving disk, and as a result 25 the brush carrier starts to move up.

Each of the trip magnets 16, 17, etc., is adapted in operating to cause a partial rotation of its associated trip rod 81, that moves all the tripping yokes 82 mounted 30 on the rod into position to engage and operate the corresponding tripping levers, controlling corresponding sets of brushes upon all of the finder switches. As it is assumed in the present case that station A' is calling and 35 that the trip magnet 16 of group A is operated, as soon as line finder C' starts to move up, the set of brushes corresponding to group A is tripped and made operative. Immediately following this in the upward 40 movement of the switch, commutator segment K is engaged by the co-operating grounded brush, and a circuit is closed that releases the trip magnet 16 and opens the starting circuit. The circuit thus closed 45 extends from ground at the K segment of the line finder commutator, by way of sequence switch contacts 209, conductor 83, through the windings of relays 23 and 33 in parallel to battery 13. When the contacts 50 35 of the relay 33 are closed in the actuation of that relay, the circuit is completed for the energization of the motor magnet of the sequence switch 200 of finder circuit C by way of contact 203 closed in 55 position 3 of the switch. This moves the switch from its third to its fourth position. Relay 23 in operating opens its contact 26, thus breaking the path to ground of the conductor 58 that theretofore had been 60 maintaining the trip magnet 16, the group 65

relay 24 and the starting relay 22, energized.

The opening of conductor 58 by the operation of relay 23 not only releases the trip magnet 16 and the group and starting relays, but also prevents the re-energization of the starting relay and of the trip magnet and group relay of any of the groups as long as relay 23 remains actuated. The duration of operation of relay 23 is controlled by a locking circuit which relay 23 closes for itself when it is actuated. This locking circuit is closed in contact 34 of the relay 23, and extends serially through the sequence switch contacts 210 of the sequence 70 switches 200 of all the finder circuits to ground. The sequence switch contacts 210 are closed in positions 2 $\frac{3}{4}$ to 1; therefore the locking circuit is completed in the contacts 210 in position 1 in the case of all the finder 75 circuits that are idle or normal, and is closed in the contacts 210 in positions 2 $\frac{3}{4}$ and beyond in all of the finder circuits that have been selected and are in use. Consequently the relays 23 and 33 are kept energized by 80 this locking circuit until the sequence switch contacts 210 of the sequence switch of the next idle finder 85 circuit in order, is the act of preselection, and is effected through the medium of a circuit closed by the relay 33 when that relay is energized by the closure of the sequence switch contacts 209 of the finder circuit that 90 has just taken the call. In operating, relay 33 closes its contacts 35 and 36. The closure of contact 35, as previously stated, causes sequence switch 200 to move its contact out of the third and into the fourth position. 95 The closure of contact 36 completes a circuit that extends by way of sequence switch contacts 211 of the finder circuit C before it has moved out of the third position and in series through such of the sequence switch 100 contacts 211 of other finder circuits as may be busy, and consequently have their sequence switch contacts in positions 4 to 17, to the contacts 211 of the first finder circuit that has its sequence switch in its 105 normal or first position, at which point the circuit is completed through the motor magnet of that sequence switch 200 to battery by way of sequence switch contacts 208 in their first position. Assuming that this is the 110 sequence switch of finder circuit D, the switch moves its contacts 210 into the second or waiting position of the switch, thus opening them and breaking the locking or holding circuit previously traced for the relays 115 23 and 33. Relay 23 in releasing closes its normal contacts 26, thus again establishing the connection to ground of conductor 58. In this manner the placing of another finder 120 circuit in readiness to receive a call makes 125 208 in their first position. Assuming that this is the 120 sequence switch of finder circuit D, the switch moves its contacts 210 into the second or waiting position of the switch, thus opening them and breaking the locking or holding circuit previously traced for the relays 125 23 and 33. Relay 23 in releasing closes its normal contacts 26, thus again establishing the connection to ground of conductor 58. In this manner the placing of another finder 130

- the starting relay 22 and the group relays 24 and trip magnets 16, 17, etc. of the various groups again responsive to the initiation of a call.
- 5 As previously explained, the circuit of the magnet 32 of the line finder C is closed to start the upward movement of the line finder brushes when the sequence switch of finder circuit C reaches its third position.
- 10 This upward movement continues until the finder switch finds the line that has initiated the call. When the brushes of the line finder encounter the terminals of the calling line, a circuit is completed for 15 the energization of the relay 37 of the finder circuit by way of the conductors 38 and 39 of the calling line, joined at the sub-station A in the telephone switch hook contacts, conductors 48 and 49 of the finder circuit, connected with line conductors 38 and 39 through the medium of finder brushes 40 and 41 and finder terminals 44 and 45 respectively, sequence switch contacts 213 and 214 closed in positions 2 to 4 20 of the switch, and the contacts of relay 52. This last mentioned relay 52, is connected by way of sequence switch contacts 212 closed in positions 2 to 4 and conductor 50 to brush 42 of the line finder, and finds a 25 circuit to ground for its energization whenever the brush 42 engages a terminal 46 of a line that is not in use for service either as a calling or as a called line, the path to ground being by way of the winding of the 30 cut-off relay 11 of the tested line. If a line is in service either as a calling or as a called line, the third conductor 53 of the line has a connection from battery by way of a 35 resistance, such as the resistance coil 64 of the finder circuit, that is relatively low in 40 value as compared with the resistance of the relay 52; and therefore when the relay 52 is brought into connection with the conductor 53 of such a line, it is shunted and 45 does not operate to connect the relay 37 with the talking conductors of the line. Therefore as the brushes are moved over the 50 terminals of the line finder, the circuit of the test relay 37 is completed to the line conductors of such lines as are not in service; and when a line not in service is found 55 with its telephone off the hook and its circuit therefore complete at the substation, as calling substation A', the relay 37 is energized and opens its contacts 54.
- The above described arrangement for identifying a calling line by means of a double test made upon each line engaged by the finder switch is not claimed herein, but is 60 one of the features described and claimed in the co-pending application of S. B. Williams, Jr., Serial No. 858,461, filed August 25, 1914.
- 65 After the relay 30 of the finder circuit was initially energized over the path by way of the sequence switch contacts 206, closed in the second position of the switch, and the contacts 25 of starting relay 22, it was maintained energized by a path extending from ground through the normally closed contacts 54 of the test relay 37, front contacts 55 of relay 30, sequence switch contacts 216 closed in positions 2 to 4, the right-hand winding of relay 30, sequence switch contact 217 closed in positions 2 to 9 and a 70 resistance coil 56 to battery. Therefore when the test relay 37 is energized and opens its contacts 54 included in this locking circuit, the relay 30 is de-energized and permits the retraction of its armatures. 75 Armature 31 of relay 30 in opening its front contact interrupts the energizing circuit for the up-drive magnet 32 by way of sequence switch contact 207 and conductor 20; and in closing its normal or resting contact, it completes a circuit for the energization of the motor magnet of the sequence switch 200 by way of sequence switch contacts 202 closed in positions 3 to 4, normal contact 31 of relay 30, and sequence switch contacts 80 208 closed in positions 18 to 14 and 2 to 7 of the switch, to ground. Thus the finding of the calling line stops the brushes of the finder switch upon the terminals of that line, and causes the finder sequence switch 85 200 to move its contacts out of the fourth position.
- In moving out of position 4, the sequence switch of the finder circuit closes, in its contacts 212 in the $4\frac{3}{4}$ to $12\frac{1}{2}$ positions, a 90 circuit for the energization of the cut-off relay 11 of the calling line, this circuit including the resistance coil 64 and being completed by way of brush 42 and terminal 46 of the line finder switch and the third or 95 local conductor 53 of the calling line. Cut-off relay 11 acts to disconnect line relay 12, and the latter relay releases its armature to remove the ground from the conductor 18 common to the group of lines in which the 100 calling line is located, and thus alter the starting condition of the line.
- As the starting condition of the calling line persists up to the moment the calling line is found and its line relay 12 released, 105 and as a second finder switch is put in readiness and made responsive to the starting circuit at an early stage in the movement of the finder switch that is hunting for the calling line, provision is made for 110 depriving the calling line and its associated group of lines of control over the starting circuit while the calling line is being hunted, and for restoring this control after the calling line is found. This is effected 115 through the agency of the timing sequence switch 100 that is associated with each of the line groups. This sequence switch 100, 120 as heretofore described, is started in the operation of the associated group relay 125 130

- and tripping magnet, and its rate of rotation is so regulated that the time of a complete rotation and return to normal of the switch is greater than the maximum time required 5 for a line finder to be started and connect with any line of the group. The result is that the line relay 12 of the calling line is always released to remove the ground from the common conductor 18 before this conductor 10 is again brought into operative relation with the starting and group tripping circuit by the closure of sequence switch contact 103 when timing sequence switch 100 returns to its normal position. Thus after 15 a finder switch has been made operative to find a calling line, the calling line and its associated lines are not only deprived of control over the starting and tripping circuits for an interval long enough to permit 20 the calling line to be connected with, no matter where it may be located in the group; but also at the expiration of this interval the group of lines has its control over the starting circuit restored independently 25 of whether the calling line is found or not, so that a failure to find the calling line for any reason does not operate to deprive the lines in the group of access to the finder switch controlling circuits.
- 30 This provision of a timing switch for governing the control of the associated group of lines over the starting and tripping circuit, prevents the possibility of a single call making operative more than a single 35 finder switch, and also cooperates in establishing such a relationship between the various groups of lines and the line finder controlling apparatus serving these groups in common, that none of the groups has undue 40 preference in securing the services of finder switches. The relationship between the finder controlling apparatus and the lines of the various groups that brings about this result and that prevents the tripping 45 of more than a single set of brushes on a finder switch, may be made clear by assuming that the four stations A, A², B and B² call simultaneously. Under these circumstances the line relays 12 of all four lines 50 are simultaneously energized and attract their armatures to apply grounds to the conductors 18 of the two groups A and B. The grounding of the conductor 18 of each of the groups, completes the circuit of and 55 energizes the relay 19 of that group. These relays simultaneously close their contacts 21 to connect the right-hand winding of the associated group relay 24 with the starting relay test conductor 57. But the 60 relay 19 of the A group in attracting its armature, opens the circuit of the test conductor 57 to the B group and the groups beyond. The consequence is that while the energizing circuit of relay 24 of the A 65 group is completed by way of the test con-
- ductor 57 to ground by way of the contacts 26 of relay 23 of the starting group, the energizing circuit of relay 24 of the B group, although closed in the contacts of relay 19 of that group, is open in the back 70 contact 21 of the relay 19 of the A group. Therefore the relay 24 of the A group is operated and relay 24 of the B group is not.
- 75 Relay 24 of the A group in operating starts the rotation of associated sequence switch 100, opens the conductor 58 to the groups beyond the A group, and closes, in its contacts 27, the energizing circuit over the conductor 58 in which circuit are included the starting relay 22, the trip magnet 16 of the associated group and the locking winding of the relay 24. The relay 22 in operating closes the starting wire 29 and starts the preselected and waiting line 80 finder. The started finder switch, in grounding commutator segment K at the end of the group-selecting stage of its movement, operates the relays 23 and 33 of the starting group E, the relay 23 opening the energizing circuit of the starting relay 22 and the trip magnet 16, and the relay 33 closing circuits that preselect the next idle 85 finder circuit and move the sequence switch of the appropriated finder circuit from its 90 third to its four position. The preselection of the idle finder circuit opens the locking circuit of the relays 23 and 33, and the relay 23 in releasing restores the circuit of the starting relay 22 to a responsive condition.
- 95 At this moment the elevator of the line finder of the first finder circuit is moving up to bring its tripped brushes into connection with the terminal of the first encountered calling line in the corresponding group A, and the starting relay 22 has just been rendered available again by the release of relay 23. The relay 19 of the A 100 group is inert, having been deenergized when the sequence switch 100 of that group starts to rotate and opens its contacts 103 an instant after the call comes in, and the relay 24 is inert, having been deenergized when relay 23 operated to open its contacts 105 110 115 120 125 130
26. Conductors 57 and 58 are therefore closed through to the B group.
- As stations B' and B² of the B group are both assumed to be calling, the relay 19 of that group is energized and the initial energizing circuit by way of test conductor 57 is closed through to the right-hand winding of relay 24 of the B group. Consequently as soon as the contacts 26 of relay 23 are closed by the release of that relay, relay 24 of the B group is energized, closes its front contacts 27 and completes the energizing circuit for operating the trip magnet 17 associated with the B group, holding the relay 24 of that group energized, and ener-

gizing the starting relay 22. This last mentioned relay immediately operates, in the manner already described, to open the initial energizing circuit for all the group relays 24 by way of test wire 57 and close the conductor 29 for starting the line finder of the second finder circuit, which circuit the starting of the first finder circuit placed in the waiting or preselected condition. The taking of the second finder circuit preselects and puts in readiness a third finder circuit, in the manner previously described. As soon as this happens the starting circuit is again rendered available to the calling lines.

When the relay 24 of the B group operated, it started the rotation of the sequence switch 100 of that group, thus opening the conductor 18 of the B group in sequence switch contacts 103. The conductors 18 of both the A and B groups are therefore open in their contacts 103, awaiting the closure of these contacts upon the completion of rotation and return to normal of their respective sequence switches 100. As the sequence switch of the A group was the first to start its rotation, it will be the first, assuming the rate of rotation of both switches to be the same, to return to normal and close its contacts 103.

As soon as sequence switch contacts 103 of the A group are again closed, the associated relay 19 is energized by way of the ground applied to conductor 18 by the line relay 12 of the waiting calling line A², the line from station A' having been found and its line relay released before the sequence switch contacts are closed. As the starting circuit was rendered available by the starting of the second finder circuit and the preselection of the third finder circuit, the starting relay 22 is therefore again energized to start the line finder of the third finder circuit and preselect the fourth finder circuit, in the manner already described. As it is the operation of the relay 24 of the A group that energizes the starting circuit and starts the upward movement of the third line finder, it is the trip magnet 16 of the A group that is energized in this case, and the corresponding set of switch brushes of the third line finder that is tripped and made operative.

When the third line finder has been started and the fourth line finder preselected and put in readiness, the starting circuit is again rendered available. Therefore as soon as the sequence switch 100 of the B group returns to normal and closes its contacts 103, the relay 19 of the B group is energized over the ground path supplied by the line relay 12 of the line to station B², the line from station B' having been connected with before contacts 103 are closed. The

result is that relay 24, trip magnet 17 associated with the B group of lines, and starting relay 22 are all energized, the relay 22 acting to start the line finder of the preselected fourth finder circuit, and the trip magnet 17 acting to trip and make operative the brushes that pass over the terminals of the B group of lines.

From the foregoing it may be seen that the organization of this invention acts, when calls are waiting in different groups of lines, to give the lines of no group undue preference over the lines of any other group in the matter of securing the services of finder circuits for taking the calls; but to distribute the finder circuits among the groups in which there are waiting lines so that the lines of one group will not have to wait for service until the lines of another group are served. Thus in the case assumed above, station A' in the A group first has its connection extended, then station B' in the B group, then station A² in the A group, then station B² in the B group. The control which the lines of each group have over the associated group tripping or selecting circuit and the common starting circuit, is governed by group apparatus which acts in the manner described to limit the frequency with which the lines of the group may start and selectively operate the finder switches to a rate less frequent than the rate at which the common starting circuit operates to start a waiting finder switch and place in readiness another finder switch.

It may also be seen that the organization of the system is such that when calls occur simultaneously in different groups only one group at a time is given control of the group selecting mechanism of a started finder switch, so that the tripping and making operative of two sets of brushes on a finder switch, and the consequent connection of the finder circuit with a line in each of the calling groups, is prevented.

The apparatus also acts in the manner already described to render the starting and group selecting circuit unavailable to the lines of a particular group after the circuit has taken a call from that group for a length of time greater than the time required for the finder switch to move into engagement with the terminals of the calling line and alter the calling condition of the line or calling relay 12, in this way preventing a single call from starting more than one finder switch.

As the invention herein presented is not concerned with the particular manner in which the connection of the calling line, after it has once been extended to a finder circuit, is further extended and completed to the line of a calling subscriber, it is not thought necessary that this part of the or-

ganization be particularly illustrated or described. The conductors of the finder circuit may be extended to the calling line through the medium of a connecting cord 5 terminating in a plug that is adapted to be inserted in a spring jack of the called line; or may be extended by means of automatic selecting and connecting switches in any one of a number of ways that are 10 well known and do not require description. In either case, it is to be assumed that the organization may be provided with such ordinary equipment as will enable the operator to receive the instructions from the 15 calling subscriber, and control the apparatus involved in the completion of the connection.

In the specific embodiment of the invention here shown, it may be assumed that 20 after the sequence switch 200 of the finder circuit has reached position 6, as a result of the finding of the calling line, it is moved out of that position and into the talking position 14 by a circuit established in the process 25 of extending the connection. In the talking position 14 of sequence switch 200, the talking conductors 48 and 49 are extended through to the apparatus with which the right-hand end of the finder circuit is as- 30 sumed to be provided, by way of sequence switch contacts 213 and 214, closed in position 14 of the switch; the third or local conductor of the finder circuit is extended through, in this position of the sequence 35 switch, by way of contacts 212 and 217 of the switch, this conductor receiving current for holding the relay 30 of the finder circuit and the cut-off relay 11 of the calling line energized; and the fourth conductor 40 with which the finder circuit is shown to be provided, and which may have a special use at this stage of the operation, is closed through by way of sequence switch contacts 207 and 208, and the closed contacts 31 of 45 relay 30.

Furthermore, the arrangement may be such that at the end of the conversation, the flow of energizing current for the relay 30, by way of the third conductor of the 50 finder circuit will be interrupted, thus permitting the closure of the back contact 55 of that relay, and the completion of a path for the flow of current through the motor magnet of the sequence switch 200 by way 55 of contacts 202, closed in the fourteenth position, and the back contact 54 of relay 37. When the sequence switch moves to position 16, it closes in its contacts 208 a path from ground for the energization of the down- 60 drive magnet 62 of the finder switch, thus causing that switch to be returned to its normal position, after which the sequence switch itself is moved to its first or normal position by the closure of an energizing circuit 65 for its motor magnet by way of se-

quence switch contacts 218, closed in position 16, and commutator segment Y of the finder switch.

While the particular embodiment of the invention disclosed, employs a sequence 70 switch for making the calling line ineffective during the period of selection, it will be understood that other well-known types of delayed-action switches or switch controlling arrangements may be substituted 75 for performing this function without departing from the spirit of the invention.

What is claimed is:

1. The combination with a plurality of telephone lines arranged in groups, of a 80 group relay for each group adapted to be operated when any line of the corresponding group calls, group selecting means under the control of said group relays, a switch for each group adapted to be operated by 85 any of the lines of that group in calling, and a common initial energizing circuit for said relays extending serially through resting contacts of said group switches and adapted when the switch of any group is operated to 90 be connected with the relay of that group and to be disconnected from the switches of other groups beyond in the series.

2. The combination with a plurality of telephone lines arranged in groups, of a 95 switch for each group operated by any line of the corresponding group in calling, a relay for each group having a holding winding and an initial energizing winding, group selecting means controlled by said relay, a 100 relay common to said groups having an energizing circuit extending serially through resting contacts of said group relays, said energizing circuit being adapted to be completed through the holding winding of any 105 of said group relays that is operated and at the same time to be cut off from the relays of the groups beyond, and a common initial energizing circuit extending through resting contacts of said common relay and se- 110 rially through resting contacts of the switches of the various groups, said circuit being adapted when any of said group switches is operated to be completed through the initial energizing winding of the corre- 115 sponding group relay and at the same time to be cut off from the switches of the groups beyond.

3. The combination with a plurality of telephone lines arranged in groups, of a 120 finder switch adapted for group and individual line selection, a group relay for each group having an initial energizing winding and a holding winding, each of said group relays being adapted in its operation to control the group selecting operation of said finder switch, means under the control of any line of each group in calling for momentarily closing a circuit through the initial energizing winding of the correspond- 125 130

ing group relay, an energizing circuit adapted to be completed through the holding winding of any one of said group relays in the operation thereof, and means operated at the end of the group selecting operation of said finder switch for rendering ineffective said holding circuit.

4. The combination with a plurality of lines, of a plurality of finder switches for making connection therewith, a starting circuit adapted upon successive energizations to start successive finder switches, means under the control of any of said lines for effecting the energization of said starting circuit, and means controlled in the energization of said starting circuit for rendering said first mentioned means temporarily ineffective to reenergize said starting circuit.

5. The combination with a plurality of lines, of a plurality of finder switches for making connection therewith, a starting circuit adapted upon successive energizations to start successive finder switches, line-controlled means for effecting the energization of said starting circuit, and a timing switch for rendering said line-controlled means temporarily ineffective to reenergize said starting circuit, said timing switch being under the joint control of said line-controlled means and said starting circuit.

6. The combination with a plurality of lines, of a plurality of finder switches for making connection therewith, a starting circuit adapted upon successive energizations to start successive finder switches, line-controlled means for effecting the energization of said starting circuit in the initiation of a call, and a timing switch actuated in the energization of said starting circuit for depriving the calling line of control over the starting circuit for a constant predetermined interval.

7. The combination with a plurality of lines divided into groups, of a plurality of finder switches adapted to be started successively by the initiation of calls by said lines, means associated with each group of lines and actuated by the initiation of a call in the corresponding group to cause a started finder switch to come into operative relation with the lines of that group, and a timing switch for each group for rendering said means again operative only at the expiration of a predetermined time interval after a previous actuation.

8. The combination with a plurality of lines divided into groups, of finder switches for making connection therewith, group selecting means for each group of lines adapted when operated to bring a finder switch into operative relation with the lines of the corresponding group, and a timing switch for preventing said group selecting means from being again operated until the expiration of an interval greater than that re-

quired for a finder switch to traverse all of the lines of the group.

9. The combination with a group of telephone lines, of a plurality of finder switches for making connection therewith, a starting circuit adapted upon successive energizations to start successive finder switches, means operated by any line in calling to energize said starting circuit, and a timing switch governing the control of the lines of said group over said starting circuit, said switch acting when said line-operated means energizes said starting circuit to deprive the lines of the group of control over said starting circuit, and acting to restore said control at the expiration of a constant predetermined interval greater than that required for said finder switch to traverse all the lines of the group.

10. The combination with a plurality of lines, divided into groups, of a plurality of finder switches for making connection therewith, means for moving said finder switches, means controlled by any line in calling for making one of said finder switches operative to connect therewith, means adapted thereafter to deprive said calling line group of control over any other moving finder switch, and means for restoring the control of said group independent of the finding of said calling line by said finder switch.

11. The combination with a starting circuit, of subscribers' lines adapted in calling to cause the closure of said circuit, a finder switch adapted to be started by the closure of said starting circuit, means operated in the starting of said finder switch for opening said starting circuit and placing a second finder switch in operative relation with said circuit, and means made operative in the placing of said second finder switch in operative relation with said starting circuit for restoring said circuit to the control of the other telephone lines.

12. The combination with a plurality of telephone lines, of a starting circuit under the control of said lines and adapted to be made operative by any line in calling, a finder switch normally in operative relation with said starting circuit and adapted to be started when said starting circuit is closed, a locking relay operated in the starting of said finder switch for opening said starting circuit and rendering the same irresponsible to the control of the associated telephone lines, a second finder switch adapted to be moved into operative relation with said starting circuit by the movement of said first finder switch, and switch contacts operated to release said locking relay when said second finder switch comes into operative relation with said starting circuit.

13. The combination with a finder switch adapted for group and individual line selection, of groups of lines extending to

groups of stationary terminals on said switch, an electromagnetic group selection controlling device for each group of terminals, an energizing circuit for each device 5 adapted to be closed upon the initiation of a call by any line in the corresponding group, means actuated in the closure of any group, energizing circuit for depriving lines of other groups of control of their respective 10 energizing circuits, means actuated at the end of the group-selecting operation of said switch to open said closed group energizing circuit and restore the other groups to the control of their circuits, and means actuated 15 after the finding of the calling line to restore the associated group to the control of its energizing circuit.

14. The combination with a plurality of lines arranged in groups, of a plurality of 20 finder switches therefor, starting and group selecting means for said finder switches, means under the control of each of said lines in calling for energizing said starting means

and the group selecting means corresponding with the group in which the calling line 25 is located, and means for preventing the reenergization of said starting and group selecting means by any line in the same group until a finder switch has made connection with said calling line. 30

15. The combination with a plurality of lines divided into groups, of a plurality of finder switches adapted for group and individual line selection, a circuit adapted upon successive energization to effect the 35 starting and group selection of successive finder switches, line-controlled means associated with each group for effecting the energization of said circuit, and means adapted to render the line-controlled means of 40 each group ineffective for an interval after it has operated to energize said circuit.

In witness whereof, I hereunto subscribe my name this 27th day of January, A. D. 1916.
